UNITED STATES PATENT OFFICE.

GEORGE H. WILLARD, OF HOPE DALE, MASSACHUSETTS, ASSIGNOR TO DRAPER CORPORATION, OF HOPE DALE, MASSACHUSETTS, A CORPORATION OF MAINE.

LATCHING MECHANISM FOR INTERMITTENT THREAD-CUTTING TEMPLES.

Application filed November 5, 1926. Serial No. 146,392.

This invention relates to a thread cutting temple of the intermittently acting type such as employed in looms provided with automatic filling replenishing mechanism 5 and in which the thread cutting mechanism is held in inoperative position by a detent latch element during the normal operation of the loom, but is rendered operative at the time of filling replenishment so as to sever 10 the filling ends left at the selvage as the result of such replenishment. One form of such an intermittent thread cutting temple is disclosed in the patent to Stimpson, No. 1,552,016, September 1, 15 1925. Therein the prime actuating element for effecting the movement of the detent latch to render the cutting mechanism operative is the usual shuttle feeler which moves when filling replenishment is to take place 20 and the movement of this shuttle feeler acting through certain controlling mechanism described in the said patent and located remote from the temple is transmitted through a Bowden wire to the detent latch. The 25 present invention in the specific form illustrated is disclosed in connection with such a construction. But the invention in its broader aspects is not restricted to this particular type of mechanism because various 30 means may be employed to effect the movement of the latching mechanism at the desired time as, for example, when filling replenishment takes place.

One object of the present invention is to 35 provide a self-contained latching mechanism which may be readily and bodily attached or secured to the head of a standard thread cutting temple and preferably without alteration thereof by utilizing the usual screw 40 employed for securing together the cap and pod of the temple head. The invention thus renders it a comparatively simple matter to equip existing looms provided with thread cutting temples with the mechanism necessary 45 to secure intermittent action of the thread cutting mechanism and without altering the temple or without even removing it from the loom.

Another object of the invention is to provide 50 a novel form of latching mechanism independent of the self-contained feature.

These and other objects and features of

the invention will appear more fully from the accompanying description and drawings and will be particularly pointed out in the 55 claims.

As the general construction and operation of various types of intermittent thread cutting temples for looms are well known and familiar to those skilled in the art, and as 60 the patent to Stimpson above referred to discloses in full detail one form of such mechanism, and as the present invention is not concerned with the particular mechanism, employed for initiating the movement 65 of the latching mechanism, it will only be necessary here to illustrate and describe a simple and preferred form of construction embodying the invention when used in connection with a controlling mechanism such 70 as disclosed in the said Stimpson patent.

In the drawings:

Fig. 1 is a side elevation partially broken away of an intermittent thread cutting temple with a preferred form of the present 75 invention mounted thereon.

Fig. 2 is a top plan view of the construction shown in Fig. 1 and partially in horizontal cross section on the line 2—2.

Fig. 3 is a detail in side elevation with 80 the cover plate of the guideway removed.

The thread cutting temple illustrated is of a well known and familiar type. The temple stand 1 is secured by bolts passing through the slot 2 therein in the usual manner to the breast beam of the loom. The temple head 3 comprises the cap 4 and pod 5 secured together by the screw 6 and nut 7. This head is provided with the usual shank 8 mounted to slide in the stand 1. 85

The cutting mechanism illustrated comprises a fixed cutter blade 9 mounted at the front of the temple head and a movable cutter blade 10 mounted to rock and reciprocate in the temple head and cooperate with the fixed blade. This movable member is provided with the usual depending heel 11 which, when struck by the lay, effects the cutting movement, while the usual spring 12 connected at its upper end to the shank 8 and at its lower end to a stud 13 projecting laterally from the heel 11 effects the movement of the movable cutter member to its rearward projected position. 95 100

The present invention is not concerned with any specific form of thread cutting temple and the construction just described is employed simply for illustration.

5 In the intermittent type of thread cutting temple, the thread cutting mechanism is normally held inoperative and in the construction illustrated, this is secured by providing the movable thread cutting member 10 10 with a laterally extending stud or projection which is engaged by a detent latch when the movable cutter member is in its inoperative or retracted position.

The present invention has to do with a 15 latching mechanism which, when in latching position, renders the cutting mechanism inoperative and, when in unlatching position, renders the cutting mechanism operative. In the construction illustrated, the 20 movement of the latch to the former position is effected by a spring and to the latter position is effected by an actuator transmitter in the form of a Bowden wire. In the construction illustrated, the Bowden 25 wire may be actuated by such a construction as disclosed in the Stimpson patent referred to upon the call for filling replenishment.

One feature of the present invention is 30 that the entire latching mechanism is embodied in a self-contained structure adapted to be readily attached to the head of the temple and preferably by means of the usual screw 6 which unites the cap and pod of the 35 temple, thus enabling the mechanism to be embodied in the loom without alteration of the temple and even without removing it from the loom. Thus existing looms in use in mills and already having thread cutting 40 temples may readily be equipped with mechanism whereby the desired intermittent operation of the temple is provided. All that 45 it is necessary to do is to attach this self-contained latching mechanism to the temple 50 head and make the necessary connections to the actuating element. If the thread cutting mechanism is not provided with a suitable part to cooperate with the latch, it may 55 readily be supplied. If the thread cutting 60 temple is of the type illustrated and there is no stud on the movable thread cutting member, it is an easy matter to furnish with the self-contained latching mechanism a new 65 movable thread cutting member having a 70 stud or projection such as 14, which may readily be slipped in place in lieu of the one in use.

The present invention, besides providing 75 a self-contained latching mechanism of a character which may be attached to the temple head, also presents a novel form of latching mechanism, whether of the self-contained 80 character or not.

In the construction illustrated, a base or 85 bracket member is provided for supporting

the latching mechanism. This base comprises a vertical portion 15 and a laterally extending projection 16 adapted to fit against and on top of the temple head and provided with an aperture fitting over the 70 screw 6 so that by means of the screw 6 and nut 7, without alteration of the temple, this base may be firmly secured in position. The portion 15 of the base is provided with a vertical guideway 17 formed by the vertical 75 flanges 18. The detent latch 19 is formed on a slide 20 mounted to slide vertically in the guideway 16. A helical spring 21 located in a slot in the slide 20 abuts at its lower end against the slide and at its upper end 80 against a lug 22 projecting from the base and thus acts normally to move the slide and detent latch downward. In the construction illustrated, a cover plate 23 is secured by screw 24 over the guideway 17. This cover 85 plate at its lower end has a vertically apertured boss presenting a connection to receive the actuation transmitter, or in this case the upper end of the Bowden wire 25, by means of which the detent latch is moved to its 90 upper or unlatching position. The upper end of the Bowden wire is shown as locked in place by a set screw 26, preferably by means of an interposed thimble 27. In the 95 construction illustrated, the movable element 28 of the Bowden wire engages and acts through a plunger 29 mounted for vertical movement in the cover plate 23 and cooperating with a projection 30 extending forwardly from the slide 20 through a slot 100 31 in the cover plate.

It will thus be seen that the plunger 29, when moved upwardly, as upon the call for filling replenishment, slides the detent latch in the vertical guideway to unlatching position releasing it from the stud 14, and thus rendering the cutting mechanism operative. When at the conclusion of the predetermined period of operation the plunger 29 drops, then the spring 21 is released to action and 110 moves the detent latch downwardly into latching position upon the next rearward movement of the movable cutter member.

The construction of the latching mechanism thus presented is of an extremely 115 simple and practical nature and one particularly adapted for use when applied to the temple head.

Having thus described the invention, what is claimed as new, and desired to be 120 secured by Letters Patent, is:

1. A self-contained latching mechanism for an intermittent thread cutting temple, the head of which presents a cap and a pod 125 united by a screw, which mechanism comprises a base, a latching mechanism for controlling the operative and inoperative position of the cutting mechanism carried by and mounted on said base, and a projection from the base fitting against the temple head 130

and around said screw, the said screw when in place acting to clamp the projection to the temple head and hold the base in place, whereby the latching mechanism may be attached to an existing temple without alteration thereof.

2. A self-contained latching mechanism for an intermittent thread cutting temple comprising a base, means for securing the base to the temple head, a guideway on the base, a detent latch mounted to slide on the guideway, means acting to slide the latch into latching position, and a connection on the base to receive an actuation transmitter by means of which the detent latch is slid into unlatching position when the cutting action is required.

3. A latching mechanism for an intermittent thread cutting temple comprising a base, means for securing the base to the temple, a guideway on the base, a detent latch mounted to slide on the guideway between

latching position, which renders the cutting mechanism inoperative, and unlatching position, which renders the cutting mechanism operative, means mounted on the base acting to slide the detent latch between the said positions as and when required to effect the intermittent operation of the thread cutting mechanism.

4. A latching mechanism for an intermittent thread cutting temple comprising a base, means for securing the base to the temple, a vertical guideway on the base, a detent latch mounted to slide on the guideway, yielding means acting to slide the detent latch downward on the guideway into latching position, and means, actuated when the cutting action is required, to slide the detent latch upward into unlatching position.

In testimony whereof, I have signed my name to this specification.

GEORGE H. WILLARD.
